Application July 18, 1933, Serial No. 681,021

20 Claims. (Cl. 170—162)

This invention relates to propellers and more particularly to propellers of the type having a plurality of blades, the angularity or pitch of which may be varied during operation.

5 In variable pitch propellers heretofore proposed and especially in instances where the blade pitch of such propellers is automatically varied during operation thereof, it has been found desirable to provide some means for limiting the reduction in the pitch of the blades in order to 10 avoid increases in engine speed above that for which the engine was designed and at which speed most efficient operation thereof is obtained.

One of the objects of the present invention is 15 to provide in a variable pitch propeller a novel construction whereby the pitch of the blades may be controlled in such a manner as to prevent the speed of the engine driving the propeller from increasing to a dangerously high value or a value 20 in excess of that speed at which the engine operates most efficiently.

Another object of the invention is to provide in 25 a propeller of the type wherein the pitch of the blades is automatically varied, a novel mechanism for limiting the reduction in the pitch of the blades after the pitch has been reduced to a predetermined minimum.

Another object is to provide a variable pitch propeller wherein the pitch of the blades is automatically varied in accordance with the propeller thrust and which embodies a novel construction 30 operable to prevent a further decrease in the pitch of the blades after the speed of rotation of the propeller has attained a predetermined value.

35 Still another object is to provide a propeller wherein the pitch of the blades is varied in accordance with thrust-responsive movement of the propeller hub relative to the driving shaft therefor and wherein a centrifugally-operable mechanism cooperates with the hub to prevent further movement thereof in one direction after a predetermined low pitch has been obtained.

40 A further object is to provide in a mechanism of the type referred to above, a novel means and method for employing the power of the propeller shaft for limiting the change in pitch of the blades in one direction after the speed of the propeller has attained a predetermined value.

45 A still further object is to provide a novel variable pitch propeller construction embodying relatively few parts, compactly arranged and operable in such a manner that the pitch of the blades will be automatically varied to yield maximum propeller and engine efficiencies under substantially all operating conditions.

The above and other objects will be more readily apparent from the following detailed description when taken in connection with the accompanying drawings. It is to be expressly understood, however, that the drawings are employed for purposes of illustration only and are not designed as an expression of the limits of the invention, reference being had to the appended claims for this purpose.

5 In the drawings, wherein similar reference characters refer to similar parts throughout the several views,

Fig. 1 is a plan view partly in section of one form of the invention;

Fig. 2 is a side view partly in section of the 15 parts shown in Fig. 1;

Fig. 3 is an axial sectional view taken on line 3—3 of Fig. 1;

Fig. 4 is a perspective view of the pitch limiting control mechanism embodied in Figs. 1 to 3;

Fig. 5 is a view similar to Fig. 1 but illustrating another form of the invention;

Fig. 6 is a side view partly in section of the parts shown in Fig. 5;

Fig. 7 is a plan view partly in section illustrating the pitch-limiting control mechanism employed in Figs. 5 and 6, and

Fig. 8 is a developed perspective view of certain 20 of the elements constituting such control mechanism.

30 Referring more particularly to Figs. 1, 2 and 3, a variable pitch propeller embodying the principles of the present invention is illustrated therein as being constituted by a rotatable engine shaft or extension thereof 10 and a hub 11 drivably 35 connected thereto, the latter being relatively movable longitudinally of the shaft in response to the thrust exerted by the propeller blades and being provided with a plurality of radially-extending sockets 12 and 13 adapted to rotatably receive the inner or root ends of propeller blades 14. As will appear more fully hereinafter, suitable means are employed for rotating the blades 40 in their respective sockets to vary the pitch of said blades during the aforesaid thrust-responsive movement of the hub relative to the shaft.

45 As shown, the propeller shaft 10 projects through a stationary member 15 which may be, for example, a portion of the crank case of the engine adapted to rotate the propeller.

50 In order to effect a drivable connection between the hub 11 and the shaft 10, a driving member or block 16 is splined to the shaft, Figs. 1 and 3, and is preferably rigidly maintained thereon by any suitable means, such as, for example, split front 55

and rear cones 17 and 18 respectively, a nut 19 threadedly received by the outer end of shaft 10 and interlocked with the front cone 17 being provided for maintaining these parts in proper operative relation with respect to the shaft. After assembly of the parts heretofore mentioned, the nut 19 is preferably locked to an outwardly-extending portion 20 of the driving block 16 by any suitable means, such as a pin 21. The hub 11 is also provided with a centrally-disposed aperture or opening 22, Fig. 3, which is adapted to receive the driving block 16, and a plurality of rows of ball bearings 23 are interposed between the driving block and hub in order to permit relative longitudinal movement between these two members in a substantially frictionless manner.

Means are provided for rotatably mounting the inner or root ends of the blades 14 within the sockets 12 and 13, and preferably such means are constituted in such a manner as to permit employment of the type of propeller blades now in common use. As shown, such means include a longitudinally split sleeve 24, the two parts thereof being firmly secured around the root ends of the blades by means of a collar 25 and an outer ring 26 threadedly received by a portion of the sleeve projecting from the hub sockets, the collar 25 being firmly pressed on the sleeve surrounding the blade root. The exterior surface of the sleeve is preferably so formed as to provide an annular shoulder 27 adapted to form an inner seat for an annular row of ball thrust bearings 28, the outer seat of said bearings being carried by a thrust ring 29 threadedly received by the outer ends of the hub sockets and serving to maintain the propeller blades 14 securely therein. Preferably, there is also provided a plurality of ball bearings 30 positioned within each socket at the inner end thereof between the hub 11 and a portion of the ring 25, in order to decrease the resistance to rotation of each blade in its respective socket.

Means are provided for interconnecting the rotatable shaft and each blade in order to effect rotation of the latter in their respective sockets to vary the pitch thereof during longitudinal or axial movement of the hub with respect to the shaft, and preferably such means are secured to the shaft rearwardly of the propeller hub. In the form of the invention illustrated, such means are constituted by a lever or link mechanism, Fig. 2 one end of which is operatively connected with the collar 25, while the other end is secured to a lateral extension or arm 31 formed integrally or otherwise secured to the driving member 16. More particularly, the above link mechanism includes a stud 32 secured to the collar 25 and extending laterally of the propeller blade and through a suitable aperture 33 formed in the hub socket. A screw member 34 is threadedly attached to the arm 31 and this last named member and the stud 32 are pivotally connected as by means of link 35. From this construction, it will be appreciated that since one end of the link mechanisms is rigidly connected to the driving member 16 which is in turn rigidly secured to the propeller shaft 10, the said mechanisms will effect a rotation of each respective blade about its longitudinal axis in order to vary the pitch during longitudinal thrust-responsive movement of the hub relative to the shaft.

In order to yieldingly oppose forward axial movement of the hub with respect to the shaft for the purpose of arresting such movement at various positions along the shaft in accordance with

the degree of thrust exerted by the blades under the existing conditions, there is preferably provided a plurality of resilient members, such as for example, coil springs 36, arranged in a circle concentrically with respect to the shaft and interposed between the hub 11 and a plate 37 secured in any suitable manner to the portion 21 of the driving block 16. It is desired to point out that the effect of springs 36 is to move the hub 11 downwardly, as viewed in Fig. 1, in order to increase the pitch of the blades, but as the hub moves upwardly, as viewed in this figure, in response to the thrust of the blades, the springs 36 will be compressed and the pitch of the blades will be decreased by the link mechanisms heretofore described, the construction being such that the springs yieldingly oppose the thrust-responsive movement of the hub and serve to arrest the latter in such a position relative to the shaft that the pitch of the blades assumed will be substantially proportional to the thrust thereof and will yield maximum propeller efficiency for the conditions of thrust imposed.

Means are provided by the present invention for predetermining the lower pitch limit of the propeller blades and preferably such means are so constituted as to predetermine the lower blade angle at a specified speed of rotation of the propeller. As shown, Figs. 1 to 4, such means are constituted by a movable disk clutch element 38 carried by and normally rotating with a flange 39 formed integrally with the driving block 16. As shown in Fig. 4, centrifugally-operable members 40, disposed on either side of the propeller hub and pivotally connected to a plate 41 formed integrally with the driving block 16 and extensions 31, are provided for moving the clutch disk 38 into frictional engagement with a stationary clutch disk 42 secured in any suitable manner to the stationary casing portion 15, it being readily apparent that when such frictional engagement occurs, the speed of rotation of the disk 38 will be retarded relative to the propeller. Any suitable means such as springs 38a are provided for insuring that the clutch element 38 is normally out of frictional engagement with respect to the disk 42. Preferably, the weighted members 40 are provided with cam portions 43a for effecting the above described movement of the clutch disk 38 and the parts are preferably so designed that frictional engagement between said disks will occur at a predetermined speed of rotation of the propeller only, there being provided a spring 43 securing one end of each of the weighted members 40 to the propeller hub in order to bias such members to inoperative position until such predetermined speed has been obtained.

As heretofore pointed out, when the disk 38 is moved into frictional engagement with the disk 42, relative rotation between the first said disk 60 and the propeller is effected and such relative movement is utilized in such a manner as to prevent further forward movement of the hub relative to the propeller shaft which would effect a further decrease in the pitch of the blades. To this end, the disk 38 is provided with a plurality of diametrically-opposed pins 44 which project through the slotted ends of links 45, the opposite ends of such links being rotatably connected with one arm of a lever 46, the latter being pivotally mounted, as by means of a screw 48, upon an upstanding ear 49 formed integrally with the plate 41. The lever 46, as shown, is provided with an arm 47 having an elongated slot 50 formed therein for reception of a stud 51 rigidly secured to the

hub 11 in any suitable manner. Preferably, the ear 49 has a guide member 52 secured thereto and provided with a slot 53 for receiving and guiding members 45 and 46 in their pivotal movement about the screw 48 and for holding said members in proper position against centrifugal force stresses. It will be readily apparent from the above that since the lever 46 is pivotally mounted on a member secured to the propeller shaft and 10 is operatively connected with the clutch disk 38 which normally rotates with the propeller, that retardation of member 38 by the stationary clutch disk 42 will serve to employ the power of the propeller shaft for moving the said lever about its 15 pivotal mounting.

In order to substantially neutralize or compensate the propeller from the effects of centrifugal torsion on the blades, the result of which would be to decrease the pitch of the blades while the 20 propeller is in operation, the collars 25 associated with the root ends of each blade are counterweighted or enlarged at diametrically-opposed sides as indicated at 54. The effect of these counterweights, as will be more particularly 25 pointed out hereinafter, is to substantially oppose or offset the centrifugal torsion on each respective blade while the propeller is rotating.

During operation, considering the shaft 10 to be rotating in a counterclockwise direction, as 30 viewed from the front, the hub 11 and blades 14 rotatably carried thereby will be moved axially of the shaft and relative thereto in response to the degree of thrust exerted by the blades, the link mechanisms referred to above being effective under such conditions to rotate the blades about 35 their longitudinal axes to vary the pitch. The springs 36 interposed between the plate 37 rigidly carried by the shaft, and the hub, will be effective during such thrust-responsive movement of the 40 hub to yieldably resist such movement and arrest the forward travel of the hub in such a position as to yield a materially increased propeller efficiency for the thrust exerted by the blades under the given conditions. When, however, during 45 operation of the propeller, the pitch has been reduced to such a value as to substantially lighten the load on the engine, the speed of the latter will increase, thus effecting an increase in the speed of the propeller. As soon as a propeller 50 speed has been obtained which corresponds to the tension of springs 43 associated with the weighted members 40, the said members 40 will move outwardly in response to centrifugal force, Fig. 4, to effect, by means of cams 43^a, frictional engagement between the clutch disks 38 and 42. As 55 soon as the former of these disks is retarded relative to the propeller, it will, by means of pins 44, rotate levers 46, 47 in a clockwise direction about their pivotal mountings 48, as viewed in Fig. 1, and thus exert a force upon the hub 11 through 60 studs 51 tending to move the latter downwardly, as viewed in Fig. 1, in opposition to the force of thrust tending to move the hub upwardly. At this particular speed, the pitch of the blades 65 will be a predetermined minimum and the hub will have a tendency to remain in a state of equilibrium as respects the longitudinal movement with respect to the propeller shaft. In the event that the speed of rotation of the propeller tends to exceed the speed above supposed, the 70 centrifugally-operable members 40 will increase the pressure between clutch disks 38 and 42 tending to produce a further oscillation of the levers 46 about their pivotal mountings, which in turn tends to move the hub 11 downwardly with a

greater force. Such an operation would tend to increase the pitch of the blades but since an increase in pitch would impose a greater load upon the engine, the net result would be a decrease in the propeller speed which would balance the supposed speed increase. It is, therefore, seen that the centrifugally-operable mechanism serves not only to limit the reduction in the pitch of the blades but also effects a governing function for the engine.

Referring more particularly to Fig. 2, as heretofore pointed out, during operation, centrifugal torsion on the blades will tend to reduce the pitch thereof, and as viewed in this figure, will tend to rotate the blade 14 in a clockwise direction, thus placing links 35 in compression and moving the hub forwardly of the shaft 10, whereupon the pitch of the blades will be decreased. However, the effect of centrifugal force on the weighted portions 54 of the collars 25 secured to the 15 roots of each blade is such as to cause the collars to tend to turn the blades in a counterclockwise direction, thus counteracting the above referred to centrifugal torsion. It is to be pointed out, however, that in certain instances it may be desirable to counteract only a portion of the torsion of the blades, in which event links 32, due to the 20 small amount of torsion existing, will always be in compression during operation of the propeller.

Another embodiment of the invention is disclosed in Figs. 5, 6, 7 and 8, the propeller in this embodiment being similar to the one heretofore described with the exception that a modified form of centrifugally-operable mechanism is provided for predetermining the lower pitch limit 30 of the blades. As shown, Figs. 7 and 8, the clutch device in this form is of the centrifugally-operated type, the same being constituted by a plurality of clutch shoes 60 adapted to be drivably connected with a drum 61 by means of projection 62 receivable in slots 63, the said drum being rigidly secured, as by means of screws 64, to a cam member 65 rotatably carried by a depending flange 66 formed integrally with the plate 41. A plurality of garter springs 67 received in grooves 68 formed in the clutch blocks are provided for 35 normally maintaining the said blocks in inoperative position, the tension of such springs being such, however, that under the action of centrifugal force the clutch blocks will move outwardly and frictionally engage a hollow stationary drum 69 secured to the casing 15. 40

It will be apparent from the above that normally the cam member 65, drum 61 and clutch blocks 60 all rotate as a unit with the propeller 55 but that after a predetermined speed of rotation of the propeller has been obtained, due to a reduction in pitch to a predetermined degree, the clutch blocks will move outwardly to frictionally engage the drum 69, thereby effecting a 60 retardation of the clutch assembly including the cam member 65. As shown more particularly in Fig. 8, the cam member 65 is provided with a pair of diametrically-opposed cam surfaces 70 with which cam rollers 71 cooperate, the said 65 rollers being secured to pins 72 which are in turn rigidly secured to the propeller hub. It will be understood from this construction that when the cam member 65 partakes of relative motion with respect to the propeller hub, the cam surfaces 70 will rotate relatively to the cam rollers 71 and will tend to move the pins 72 downwardly, as viewed in Fig. 8, to thus arrest further thrust-responsive movement of the hub tending to decrease the pitch of the blades.

In order to efficiently withstand the thrust of the cam member 65 against the driving block 16 during operation of the said cam member, and to equalize the tension on the diametrically-opposed pins 72, the said member is provided with an internal ledge 73 having a pair of diametrically-opposed slots 74 formed therein for reception of projections 75 formed integrally with a bearing race 76 which latter cooperates with 10 bearings 76^a. Preferably, the ends of the slots 74 and the extremities of the projections 75 are slightly rounded in order to form a two-point support for the cam member 65, it being apparent from this construction that the portions 15 of the cams 70 engaged by the cam rollers constitute in effect equal arms of a lever whose fulcrum includes the points of engagement between projections 75 and slots 74. As shown in Fig. 5, the pitch of cams 70 is such that thrust-responsive 20 movement of the hub to decrease the pitch of the blades will not be prevented during normal operation of the propeller.

Preferably, means are provided for adjusting the tension of one or more of the garter springs 25 67 in order to vary the speed at which the clutch blocks 60 engage the drum 69 and hence in order to vary the lower pitch limit of the blades. As shown, Fig. 8, adjacent ends of a pair of clutch blocks 60 are cut away to form a recess 71 for 30 receiving said adjusting means, the latter being constituted by a shaft 77 rotatably mounted in the drum 61, the said shaft having a wheel 78 secured thereto in any suitable manner. The ends of one of the garter springs 67 are secured 35 to diametrically opposite portions of the wheel 78 and the tension of this spring may be varied by rotating the said wheel through a notched adjusting member 79 secured to the shaft and readily accessible through an opening in the 40 drum 69 normally closed by cover plate 80. A spring detent 81 carried by the drum 61 is adapted to cooperate with the notched periphery of the adjusting member 79 in order to maintain the latter in a predetermined position after adjustment of the tension of the spring.

It will thus be appreciated from the foregoing description that the present invention provides a relatively simple but effective method of preventing the speed of the engine driving the propeller from increasing beyond a predetermined value, which might otherwise occur if the pitch of the propeller blades were materially reduced. The construction also prevents the occurrence of this last named condition and thus enables operation of the engine and propeller at maximum efficiencies. By utilizing the power of the propeller shaft for arresting movement of the propeller hub and consequent further decrease in the pitch, it will be apparent that a relatively light-weight and compactly arranged centrifugally-operable control mechanism may be employed, which is a distinct advantage in aircraft installations wherein a light-weight construction is extremely desirable.

While two embodiments of the invention have been herein disclosed and described, it is to be understood that the same is not limited thereto, but may be embodied in various forms without departing from the spirit thereof, as well understood by those skilled in the art. Reference will, therefore, be had to the appended claims for a definition of the limits of the invention.

What is claimed is:

1. In a variable pitch propeller, a rotatable shaft, a hub drivably connected therewith, a plu-

rality of blades rotatably mounted in said hub, means for automatically varying the pitch of said blades during operation of the propeller, and means separate from said pitch varying means for limiting the change in pitch in one direction comprising a member normally rotating with said propeller and adapted to be retarded to rotate relative thereto.

2. In a variable pitch propeller, a rotatable shaft, a hub drivably connected therewith, a plurality of blades rotatably mounted in said hub, means for automatically varying the pitch of said blades during operation of the propeller, a member normally rotating with said propeller, and means for retarding the movement of said member relative to the propeller to limit the reduction in pitch of the blades.

3. In a variable pitch propeller, a rotatable shaft, a hub drivably connected therewith, a plurality of blades rotatably mounted in said hub, means for automatically varying the pitch of said blades during operation of the propeller, and means for limiting the reduction in the pitch of the blades at a predetermined speed of rotation of the propeller including a member normally rotating with said propeller, and a centrifugally-operated device for retarding the rotation of said member relative to the propeller.

4. In a variable pitch propeller, a rotatable shaft, a hub drivably connected therewith, a plurality of blades rotatably mounted in the hub, the latter being movable longitudinally of said shaft in response to the thrust of the blades, means operable to vary the pitch of said blades during such thrust-responsive movement of the hub, and means for limiting the change of pitch in one direction comprising a member rotating with said propeller but adapted to be retarded relative thereto.

5. In a variable pitch propeller, a rotatable shaft, a hub drivably connected therewith, a plurality of blades rotatably mounted in the hub, the latter being movable longitudinally of said shaft in response to the thrust of the blades, means operable to vary the pitch of said blades during such thrust-responsive movement of the hub, a member normally rotating with said propeller, and means for retarding said member to effect rotation thereof relative to the propeller for limiting the reduction in the pitch of the blades.

6. In a variable pitch propeller, a rotatable shaft, a hub drivably connected therewith, a plurality of blades rotatably mounted in the hub, the latter being movable longitudinally of said shaft in response to the thrust of the blades, means operable to vary the pitch of said blades during such thrust-responsive movement of the hub, and means for limiting the reduction in the pitch of the blades at a predetermined speed of rotation of the propeller including a member normally rotating with said propeller, and a centrifugally-operated device for retarding said member to effect relative rotation thereof with respect to said propeller.

7. In a variable pitch propeller, a rotatable shaft, a hub drivably connected therewith, a plurality of blades rotatably mounted in the hub, the latter being movable longitudinally of said shaft in response to the thrust of the blades, means operable to vary the pitch of said blades during such thrust-responsive movement of the hub, and means for limiting movement of the hub with respect to the shaft in a direction to decrease the pitch of the blades comprising a member normally rotating with said propeller, and means oper-

able in response to centrifugal force at a predetermined speed of rotation of the propeller for effecting movement of said member relative to the hub.

- 5 8. In a variable pitch propeller of the type having a plurality of blades the pitch of which varies automatically in accordance with the thrust thereof, centrifugally-operable means for substantially overcoming the torsion of the blades 10 while the propeller is in operation, and means for predetermining the lower pitch limit of the blades, said last named means including a member normally rotating with said propeller, centrifugally-responsive means operable at a predetermined speed of rotation for effecting relative movement between said member and the propeller and means for operatively associating said member and blades.

9. In a variable pitch propeller, a rotatable 20 shaft, a hub drivably connected therewith, a plurality of blades rotatably mounted in the hub, the latter being movable longitudinally of said shaft in response to the thrust of the blades, means operable to vary the pitch of said blades 25 during such thrust-responsive movement of the hub, means operable by power derived from said propeller while in operation for limiting movement of the hub in a direction to decrease the pitch of the blades, and centrifugally-responsive means operable at a predetermined speed of rotation of the propeller for rendering said second 30 means operable.

10. In a variable pitch propeller, a rotatable shaft, a hub drivably connected therewith, a plurality of blades rotatably mounted in the hub, the latter being movable longitudinally of said shaft in response to the thrust of the blades, means operable to vary the pitch of said blades during such thrust-responsive movement of the hub, a member normally rotating with said propeller, centrifugally-responsive means operable at a predetermined speed for retarding said member, and means for connecting said member to said hub, whereby at said predetermined speed, 45 further movement of the hub in a direction to decrease the pitch of the blades will be prevented.

11. A propeller for aircraft comprising a plurality of blades, means for rotating said blades, means responsive to the thrust of the blades 50 and including a longitudinally-movable hub for changing the pitch of said blades, and other means cooperating with said hub for predetermining the lower pitch angle of said blades, said other means including a member normally rotating with said propeller and connected with said hub, and centrifugally-responsive means for retarding said member to effect relative movement between the latter and the propeller.

12. In a variable pitch propeller, a rotatable 60 shaft, a hub drivably connected therewith, a plurality of blades rotatably mounted in the hub, the latter being movable longitudinally of said shaft in response to the thrust of the blades, means operable to vary the pitch of said blades during such thrust-responsive movement of the hub, a member normally rotating with said propeller, a plurality of levers pivotally mounted with respect to said shaft and connected with said member and hub, and means for retarding the movement 65 of said member with respect to the propeller whereby said levers will prevent further movement of the hub in a direction to decrease the pitch of the blades.

13. In a variable pitch propeller, a rotatable 70 shaft, a hub drivably connected therewith, a

plurality of blades rotatably mounted in the hub, the latter being movable longitudinally of said shaft in response to the thrust of the blades, means operable to vary the pitch of said blades during such thrust-responsive movement of the hub, a member normally rotating with said propeller, a lever disposed on either side of the hub and pivotally mounted with respect to said shaft, said levers being connected with said member and hub, and means responsive to centrifugal force for retarding the movement of said member relative to the propeller whereby said levers will be moved about their pivotal mountings and will oppose further movement of the hub in a direction to reduce the pitch of the blades after a predetermined speed of rotation of the propeller has been attained.

14. In a variable pitch propeller having a plurality of blades, a rotatable shaft, a hub movable longitudinally of said shaft, a driving member secured to said shaft and disposed between the latter and the hub, said member being provided with a pair of laterally-extending arms positioned rearwardly of the hub, means connecting said arms and blades to vary the pitch of the latter during movement of the hub longitudinally of the shaft, a clutch disk carried by said member and normally rotating therewith, means including a pair of centrifugally-responsive devices operable at a predetermined speed of rotation of the propeller for retarding movement of said clutch disk, and means connecting said disk and said hub 30 and pivotally connected with said driving member for preventing further movement of the hub relative to the shaft at said predetermined speed. 35

15. In a variable pitch propeller having a plurality of blades, a rotatable shaft, a hub movable longitudinally of said shaft, a driving member secured to said shaft and disposed between the latter and the hub, said member being provided with a pair of laterally-extending arms positioned rearwardly of the hub, means connecting said arms and blades to vary the pitch of the latter during movement of the hub longitudinally of the shaft, a clutch disk carried by said member and normally rotating therewith, a stationary member, centrifugally-responsive means for moving said disk into engagement with said stationary member for retarding movement of the disk to effect relative rotation between the latter and the propeller, and means dependent upon relative rotation between the propeller and disk for moving the hub in one direction longitudinally of said shaft.

16. In a variable pitch propeller, a rotatable 55 shaft, a hub drivably connected therewith, a plurality of blades rotatably mounted in said hub, means for automatically varying the pitch of said blades during operation of the propeller, a member normally rotating with said propeller, and means for retarding the movement of said member relative to the propeller to limit the reduction in pitch of the blades, said last named means including a centrifugally-operated clutch mechanism.

17. In a variable pitch propeller having a shaft and a plurality of blades drivably connected thereto, means for automatically varying the pitch of the blades during operation of said shaft, means for utilizing the power of said shaft when in 70 operation for limiting the decrease in the pitch of the blades, and centrifugally-operated means for controlling the operation of said second named means.

18. In a variable pitch propeller having a shaft 75

- and a plurality of blades drivably connected thereto, means for automatically varying the pitch of the blades during operation of said shaft, means for utilizing the power of said shaft when 5 in operation for limiting the decrease in the pitch of the blades, and a centrifugally-operated clutch mechanism rendering said second named means operable at a predetermined speed of rotation of the propeller.
- 10 19. In a variable pitch propeller, a rotatable shaft, a hub drivably connected therewith, a plurality of blades rotatably mounted in said hub, means for automatically varying the pitch of said blades during operation of the propeller, and
- centrifugally-controlled power operated means separate from said pitch-varying means for limiting the variation in pitch of said blades.
20. In a variable pitch propeller, a rotatable shaft, a hub drivably connected therewith, a plurality of blades rotatably mounted in said hub, means for automatically varying the pitch of said blades during operation of the propeller, and means separate from said pitch-varying means and operated by power from said rotatable shaft 10 at a predetermined speed for limiting the reduction in pitch of said blades.
